CANNING APPARATUS

Filed May 20, 1929

BY Perry J. L. Webster ATTORNEY

UNITED STATES PATENT OFFICE

WILBUR E. LACEY, OF ISLETON, CALIFORNIA

CANNING APPARATUS

Application filed May 20, 1929. Serial No. 364,460.

This invention relates to the canning of food products, especially asparagus and particularly to the initial step of placing the asparagus in the cans prior to the cooking of same.

At present it is necessary for the cannery operators to gather the asparagus stalks up in their hands in small bundles, and place the same upright in the cans. This is a somewhat slow procedure, as is well known to those in the industry, since, among other things, the asparagus is somewhat soft owing to the prior treatment to which it has been subjected and it is consequently delicate to handle and tends to catch on the edge of the can while being inserted vertically therein. It is also hard to fill the can to a proper extent with any kind of speed.

The principal object of my invention is to provide an appliance which enables asparagus of the requisite amount to fill a can to be initially laid down flat and to be then injected all at once into the can without danger of any stalks catching on the edge of the can. The efficiency of my improved means of packing asparagus into the cans over present methods is such that two operators are able to easily fill as many cans in a given time as now requires the services of eight or more operators.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of the apparatus in position to be filled with asparagus.

Fig. 2 is a similar view showing the can interposed in place in connection with the receptacle after the latter has been filled.

Fig. 3 is a longitudinal section of the apparatus in connection with a can showing the asparagus after it has been transferred from the receptacle to the can.

Fig. 4 is a similar view showing the adjustment of the parts to enable the device to be operated in connection with short cans.

Referring now more particularly to the drawings and the characters of reference marked thereon, the numeral 1 denotes a pair of transversely spaced guide members which are connected at their ends by flat orificed straps 2 or the like, which are adapted to rest on and be secured to the work-bench or table 3.

The members 1 form support and guiding means for the asparagus receiving receptacle 4 which is substantially the same size and shape as a standard asparagus can 5 and is disposed on the slide with its major axis in a horizontal plane.

The front end of the receptacle is open while the top is in the form of a lid 6 hinged along one side of the same as indicated at 7.

Freely fitting in the receptacle is a thin plunger 8 substantially the same size and area as the cross sectional area of the receptacle, which plunger is rigidly supported by a horizontal rod 9 which projects through the back of the receptacle to a supporting bracket 10 fixed in connection with the adjacent end of the guide members 1. The length of the rod between the plunger and bracket is substantially the same as that of the receptacle so that when the latter is slid to its limit of movement in the direction of the bracket the plunger will lie adjacent the front open end of the receptacle as shown in Fig. 3.

Mounted in connection with the lid on the top of the same is a strap 11 which projects beyond the open end of the receptacle a distance approximately equal to the length of the can 5 and which terminates at its outer end in a depending extension 12 to engage the adjacent end of the can as shown in Figs. 2 and 3. A handle 13 connected to the strap over the lid enables the latter to be opened and closed and the receptacle and can to be moved lengthwise along the slides.

In operation the receptacle is first shifted along the sides so that the plunger is at the back end of the receptacle and the lid is then

opened as shown in Fig. 1. The asparagus, which is already cut to the proper length, is then laid horizontally in the receptacle from above until it is full. The can is then placed in the slide ahead of the receptacle so that its open top then abuts against the open end of the receptacle.

The lid is then closed which at the same time causes the extension 12 to move into engaging position with the outer or bottom end of the can. The handle is then moved toward the opposite end of the guides, which causes the stationary plunger to be relatively shifted in position in the can so that the asparagus is transferred as a unit from the receptacle to the can. When the receptacle reaches its limit of movement the lid is thrown open, the can is removed and the receptacle is shifted to its original position relative to the plunger ready for the next filling operation.

Since standard asparagus cans are of two lengths but the same cross sectional area I mount the strap 11 on the lid for sliding movement relative thereto so that the distance from the extension 12 to the adjacent end of the receptacle may be altered to conform to the different lengths of cans. To hold the extension at a proper distance for long cans the strap has a stop 11^a at its end opposite to the extension for engagement with the back of the receptacle. Said strap is also arranged to have a removable stop 14 applied thereto somewhat ahead of the stop 11^a to also engage the back of the receptacle and to then hold the strap extension at the proper distance from the receptacle to cooperate with the short can 5^a as shown in Fig. 4. To control the normal position of the plunger relative to the open end of the receptacle for such short cans a removable pin 15 or the like is applied to the rod 9 in a position to prevent outward movement of the receptacle relative to the plunger a greater distance than the length of the short-cut asparagus or can.

While I have herein especially described and shown the device as intended for the canning of asparagus, said device is not limited to this particular use since it is equally adaptable for canning other products such as sweet potatoes, string beans, and the like.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

65 1. A can filling device including a recep-

tacle of substantially the same size and shape as a can, and disposed with its major axis horizontally, said receptacle being open at one end and along the top, a hinged lid for the top, a support along which said receptacle is slideable and also serving as a support for an open topped can when disposed with its open end abutting against the open end of the receptacle, a plunger in the receptacle rigid with the support, and means mounted in connection with the receptacle for engagement with the outer end of the can to enable said can and receptacle to be moved as a unit along the support.

2. A can filling device including a receptacle of substantially the same size and shape as a can, and disposed with its major axis horizontally, said receptacle being open at one end and along the top, a hinged lid for the top, said receptacle being adapted to be associated with a can disposed with its open end abutted against the open end of the receptacle, means for disengageably maintaining the can and receptacle thus associated with each other, and a plunger in the receptacle; said plunger and receptacle being movable lengthwise relative to each other whereby to cause articles initially placed in the receptacle between the open end thereof and the plunger to be transferred to the can with such movement.

3. A can filling device including a receptacle of substantially the same size and shape as a can, and disposed with its major axis horizontally, said receptacle being open at one end and along the top, a hinged lid for the top, a support along which said receptacle is slideable and also serving as a support for an open topped can when disposed with its open end abutting against the open end of the receptacle, a plunger in the receptacle rigid with the support, a strap mounted in connection with the lid and extending beyond the open end of the receptacle, an angular extension on the outer end of said strap for engagement with the outer end of the can when the lid is closed, and a handle mounted in connection with the lid.

4. A structure as in claim 1, with a common handle for operating the door and for moving the receptacle and can.

5. A can filling device including a receptacle of substantially the same size and shape as a can, and disposed with its major axis horizontally, said receptacle being open at one end and along the top, a hinged lid for the top, a support along which said receptacle is slideable and also serving as a support for an open topped can when disposed with its open end abutting against the open end of the receptacle, a plunger in the receptacle rigid with the support, stop means for limiting the relative movement of the plunger away from the open end of the receptacle, a strap slidably mounted on the lid for movement length-

wise thereof and extending beyond the open end of the receptacle, a member on the outer end of the strap for engagement with the outer end of the can when the lid is closed, and stop means between the strap and receptacle for adjusting the distance between the said member and the outer end of the can to conform to the limit of spacing possible between the open end of the receptacle and the plunger.

10 In testimony whereof I affix my signature.

WILBUR E. LACEY.
